UNITED STATES PATENT OFFICE.

CHARLES W. ECCLESTON, OF LOS ANGELES, CALIFORNIA.

RIFFLED PNEUMATIC CONCENTRATING-TABLE FOR GRAVITATIONAL SEPARATION OF COMMINUTED MATERIAL.

1,343,497.

Specification of Letters Patent. Patented June 15, 1920.

Application filed June 24, 1918. Serial No. 241,707.

To all whom it may concern:

Be it known that I, CHARLES W. ECCLESTON, a citizen of the United States, residing at Los Angeles, in the county of Los Angeles and State of California, have invented a new and useful Riffled Pneumatic Concentrating-Table, for Gravitational Separation of Comminuted Material, of which the following is a specification.

- 10 This invention relates to a transversely inclined concentrating table having a differential reciprocating motion which carries the comminuted material longitudinally forward toward the concentrates end of the table. Said table is adapted for the treatment of masses of comminuted materials containing particles of substances differing in specific gravity, which causes them to separate while more or less supported and buffeted by air expanded underneath the mass while the mass is in air of predetermined pressure such as atmospheric pressure, and subjected to impulses longitudinally of the table and to gravitational forces; and by means of which impulses the heavier particles are impelled along the table with greater velocity than the lighter particles, so that the heavier materials being less susceptible to the buffeting impulses and being driven by the longitudinal impulses will out-travel the lighter material in one direction, while the lighter materials, being more subject to the buffeting impulses, and not being subject to such rapid longitudinal travel, flow laterally upon the buffeting surface formed at the pressure drop zone, and responsive to gravitational forces, down the table slope and off of the table at the tailings discharge side thereof.
- 15 Tables of the general character above referred to are well known, and the permeable element through which the air is introduced to the under side of the flowing mass of comminuted material to be gravitationally separated, classified or concentrated, has heretofore been subject to conditions which make the operation of such machines for any length of time very inconvenient and expensive. Heretofore in
- 20 machines of this character the permeable elements through which the air is forced beneath the mass of materials to be separated according to specific gravities has been some form of fabric, or else a metal
- sheet slotted or punched with numerous holes; but all such concentrating tables have been subject either to clogging with dust, or to excessive blast-like action of the air, depending on whether the material is canvas of hard spun filament, or a very fine wire cloth or some other material, constituting a permeable sheet in which the perforations are of constant dimensions. In all former machines of this class the volume of air passing therethrough is dependent upon constant orificial dimensions and the effect of increasing air pressures is to discharge the air with some velocity, as jets through numerous small nozzles. So far as I am aware, no pneumatic mineral concentrator using a fabric as its permeable table top has ever been produced, which is not subject to frequent clogging of the air delivery element; and this has been a great source of loss and of expense in the operation of this class of machines; for the clogging, which occurs inevitably therewith, necessitates frequently stopping the work and removal and renewal of the separating sheet; or replacement with new. The finer and more delicate separations cannot be effected with the slotted sheet metal top, and such material is only employed for the coarser classifications and separations.
- 25 I have discovered that all the inconveniences, troubles, delays and expenses above referred to with respect to pneumatic separators or concentrators for fine work are caused by the use, as aforesaid, of fabric in the construction of the table top or permeable element, because of the permanent and fixed character of the orifices through which the upwardly directed air flow occurs.
- 30 I have also discovered that the remedy is simple and cheap and easily applied, so that at a low cost any of the machines in which these troubles have been constantly present and well known for years, may be quickly transformed into machines to which all such troubles are foreign and in which they will never more occur.
- 35 An object of this invention is to provide a pneumatic separator free from all liability to the great loss above referred to, and adapted for constant operation day and night for an indefinite period of time without variations in the character, quality and

quantity of concentrates and tailings produced from a determined comminuted product to be separated according to gravities.

The principle of the invention and discovery is the discarding of the fabric and the slotted sheet metal forms of permeable concentrator table top and the replacing them with a permeable stretchable rubber sheet of definite character as will more fully 10 hereinafter appear.

The invention is broadly new and pioneer in this particular. That is to say, I have discovered there is an easy solution for the difficulties heretofore encountered and for 15 the great expense now common to all so-called dry or pneumatic concentrators, and that the remedy resides in the construction of an apparatus with a permeable top made of a resilient, stretchable thin rubber sheet, 20 punctured with numerous fine normally closed slit-like punctures, so as to allow the air to expand the punctures into perforations during the operation of the machine, and to cause the perforations to completely 25 close after such air imposed expansion has ceased; and the invention is regarded as broadly new and pioneer in this respect.

An object of the invention is to make 30 provision for more gently diffusing the expanding upwardly directed compressed air throughout the mass of comminuted material at predetermined zones of pressure drop, so that the particles will all receive about the 35 same application of buoying force at any particular zone under a certain pressure drop, thus allowing the differential motion and the table inclinations to operate uniformly on all particles of the same specific gravity throughout the respective zones and 40 causing the separations to be effected rapidly with the highest precision.

This invention marks a broadly new, primary and pioneer departure from former dry concentrating practice in that the air 45 which is delivered to the underside of the comminuted mass in which the separation is to be effected, is delivered through openings varying in size and direction according to the conditions of operation; such as the relations of the weight of the comminuted body to the expansive force of the pneumatic pressure by which the air is applied to such body with varying pressure drop at various 50 zones; and involves also an automatic adjustment to the atmospheric pressures of varying altitudes; and, in fact, the operation of the machine involves a new method of concentration which consists in transmitting 55 differential motion and applying pneumatic pressure to the underside of a comminuted mass by means of a thin stretchable india rubber sheet through orifices that are open only during a stretching of the sheet responsive to the pneumatic pressure and 60 varying in pressure drops at various zones 65

and that are subject to increase and decrease in direct relation to the pneumatic and atmospheric pressures and to the weight of that portion of the comminuted mass which is directly above the orifice through which 70 the air issues to support said mass.

Another object is rapid and perfect separation of all the values from the gangue.

An object of the invention is to provide a pneumatic ore concentrator table in which 75 the air from the air chamber will not pass through the table top until the pressure underneath the table top is equalized throughout so that the upward flow of air at any structure point of the table will correspond 80 to that at any other point of like structure irrespective of the location of the air supplying pipe.

Another object is to subject the comminuted material to various pressure drop 85 zones and to various applications of the gravitational and pneumatic forces at each period of travel from riffle to riffle so that the particles in the material will be thoroughly buffeted and shaken apart in their 90 progress from zone to zone over the table top, thus to facilitate the separation according to specific gravities.

Other objects and advantages may appear from the accompanying drawings, the 95 subjoined detail description and the appended claims.

The invention may be carried out in various forms and the accompanying drawings illustrate the invention in a form I at present deem most desirable.

Figure 1 is a diagrammatic end elevation of a riffled dry concentrator constructed in accordance with this invention.

Fig. 2 is an enlarged fragmental cross-sectional elevation of the riffled dry concentrator table shown in Fig. 1 out of action. Line x^2 , Fig. 8, indicates the plane of section.

Fig. 3 is a fragmental elevation of the 110 concentrator table top in section on line x^3 , Fig. 7; three riffles and fragments of their supports being shown. The thickness of the punctured sheet is exaggerated and perforations shown as being viewed at right angles 115 to their length. A mass of comminuted material is shown in a state of partial separation as it may appear during the operation.

Fig. 4 is a fragmental view of the sheet in section on line x^4 , Figs. 3 and 7; viewing 120 the perforations from a sectional plane parallel to the riffles and oblique to the sides of the slits.

Fig. 5 is a full-size detached fragmental view of the normally unstretched dry-concentrator table top sheet or permeable medium shown in Figs. 2, 3 and 4; the width of the punctures being exaggerated.

Fig. 6 is an enlarged fragmental plan of the surface sheet or permeable medium out 130

of action as shown in Fig. 2. The slit-like punctures are shown proportionally enlarged in both width and length.

Fig. 7 is a fragmental plan on the scale 5 of Fig. 5 showing the top face of the permeable medium as the same may appear when stretched in action.

Fig. 8 is a broken fragmental plan in reduced scale, of the table shown in Fig. 1. 10 The scale is too small to exhibit the punctures.

Fig. 9 is an enlarged fragmental elevation in longitudinal section. The rubber sheet is shown stretched.

15 Fig. 10 is a perspective and cross-section on the scale of Fig. 6 of the needle and plate by which the puncture shown in Fig. 6 may be successively made.

1 indicates a thin highly elastic stretchable india rubber sheet having punctures 2 therethrough and supported at intervals by narrow bars 3 that also serve as wind brakes and as supports for the riffles 4 which are superposed on the sheet and clamp the sheet 25 to the bars. Said sheet and riffle-supporting wind brake bars are carried by the table frame 5 in which is formed the air pressure chamber 6, the bottom of which chamber is formed by a metal sheet 7 through which air 30 is admitted to said chamber by pipe 8, and which during operation is impermeable to the air pressure produced through such pipe.

The riffled pneumatic concentrator table thus formed is supported by the shaking frame 9 supported by springs 10 and operated by a differential motion device 11 of any of the well-known forms commonly used for giving differential reciprocating motion to separating tables.

40 The numerous small punctures 2 are normally closed by the elasticity of the rubber sheet and are opened by action of the pneumatic pressure during the operation of the concentrator.

45 The top surfaces of the riffles of the table thus constructed lie about or exactly in a common plane that, in practice, may be adjusted as to slant by any well-known means, not shown; and provision is made 50 for the free flow of comminuted material over said surface, and free discharge of tailings over said riffles in one direction, and free discharge of values in another direction along the channels 12 between the riffles. The speed with which the discharge of tailings and values occurs will depend upon 55 the slope adjustment of the table as is well-known in the art.

In tables of the character referred to, the 60 material to be treated is fed to the surface of the table top by any suitable means, not shown, and said surface is in air of lower pressure than that of the compressed air chamber; so that the compressed air which 65 opens the punctures and flows out through

the sheet, buoys up the material in the air of predetermined lower pressure to which the compressed air flows.

In practical operation when air is compressed into the compressed air chamber 6, 70 it stretches and bows the india rubber sheet upward, thus forming a ridge 12 along the spaces between the riffles and opening the slits on the upper side to a greater extent than below; and thus the expanding air is 75 given a diffusing direction away from the mid-line of the slit-like openings and the tendency of impelling the air as from a multitude of nozzles is avoided. The air streams are also modified by their contact, 80 under pressure, with the soft rubber walls of the slits; thus tending to set up along the mid-lines of the slits, respectively, laterally expanding currents that frictionally act upon the air that is in frictional contact 85 with the soft rubber walls of the slits; the result being a tendency to more immediately spread the escaping air over the inter-slit spaces and thereby making a practically uniform sustaining and constantly upwardly 90 moving and upwardly and laterally expanding air body at each particular zone above the table.

By arranging slits in rows side by side at close intervals and spacing the rows a 95 greater distance apart, the expansion of the air endwise of the slits bridges the space between the rows with compressed air of somewhat less expansive force than that of the expanding air directly above the rows of 100 slits; so that as the comminuted material flows over the surface, it is subject to gentle successive rising and falling action caused by the differences in upward pressures; this action, tending to assist in the separation 105 of the particles by an undulating or riffled buffeting action on the stream of flowing material that is carried along commingled with the compressed and expanding air medium that supports the comminuted mass 110 above the top of the table.

The rows of punctures are arranged in parallelism at regular intervals apart; and the spaces between the riffles are preferably multiples of the spaces from center to center 115 of the rows of punctures so that a row of punctures will lie close to the approach side of each riffle.

The sheet forming the top of the table is clamped to the shaking frame 9, and the 120 springs 10 which support said frame are carried by posts 13. The differential motion is applied to the table by any differential motion device well known in the arts connected to loop 14 opposite to the concentrates end 14' of the table. The air is supplied by pipe 8 from any suitable source such as the cycloidal blower 15 connected to the pipe by a flexible hose 16, which is slack to permit reciprocating motion of the table. 130

The riffles 4 are of gradually reduced depth from the head of the table toward the concentrates end thereof as shown in Fig. 9.

5 The stretchable finely punctured sheet 1 is preferably of india rubber, thus securing an impervious character capable of holding fluids such as air and water, except when the sheet is stretched, and also possessing great elasticity and durability under the conditions imposed by the work.

10 The normally closed punctures 2 may be produced in various ways, and in the rubber sheets I have used, I have produced the punctures by means of a pointed needle 17, 15 having a triangular cross-section with sharp corners and working through a thrust plate 18 having a hole 19 that fits the needle at the thickest portion thereof which passes through the sheet. Said needle may be operated 20 by means of an ordinary sewing machine mechanism not shown, fitted with said plate; parallel lines of punctures being made by running the sheet through the sewing machine in the same manner as 25 though the sheet were being stitched by the machine. These punctures may be made as large or small as deemed advisable, and the rows as close together as desired; and I have employed punctures consisting of slits 30 each of which is about $\frac{3}{2}$ of an inch in length extending through a sheet somewhat less than $\frac{1}{2}$ of an inch in thickness. These proportions or others may be employed as 35 found advisable. The triangular needle suitable for making holes of the character stated is $\frac{3}{2}$ inch across the face at the largest cutting part.

40 It is deemed preferable to make the punctures in the form of slits so that as the material is stretched, the punctures will be expanded according to the angle of the sheet and the amount of stretch to form openings therethrough that are very narrow and fine, but capable of allowing considerable air 45 under pressure to flow through.

46 I find that the needle above described does not form a three-cornered hole in the rubber, but makes a slit that opens and closes as the expansion and contraction occurs.

50 It is understood that the sheet may be of any suitable thickness and that various lengths of slits may be made in such material, the principle being that the material shall be of such character that when the 55 sheet is normal, that is to say, not stretched, the slits will be closed and the sheet will be impervious to the passing of fluids and other highly mobile materials under a limited pressure which may be predetermined for 60 the different concentrator tables.

65 I have operated the table to good advantage with a pressure of from one to four pounds pressure per square inch with $\frac{1}{2}$ to $\frac{5}{8}$ inch depth of pulp, but do not limit the operation to such pressures or depths.

The slits are preferably arranged oblique to the slit rows, to the riffles, to the table slope, and to the flow of material, so that practically every particle of the material passing over the surface while in action, 70 must pass successively over a perforation and then over an imperforate portion of the sheet and so on, and the air currents at the surface of the sheet will have a superior agitating effect upon the mass.

75 By reference to Fig. 3 it will be seen that in action, the mass of comminuted material flows freely over the tops of the riffles 4 as though subject only to the action of the differential motion and the force of gravity. 80 The air enlivens the pulp so that it is highly fluid. It is noted that there are several zones of operation as *a*, *b*, *c*, *d*, *e*, *f*, *g*; and that the comminuted material in the respective zones is differently acted upon by the 85 forces at work. At the zone *a* the comminuted material flows over the top of the riffle and is subject only to the forces of gravity, to friction of the riffle, and to the differential motion.

90 As the pulp passes from the riffle into zone *b* it falls directly by gravity and is less subject to the force of the differential motion. At the onward side of the zone *b* and throughout the zones *c*, *d*, *e* and *f* the mass 95 is subject to the enlivening action of the expanding air that issues from the perforations 2 which have been opened up by the expansive force of the air from the chamber 6. The air from the perforations in zone *c* 100 is directed upward aslant toward the downwardly onflowing material of zone *b*: As such material passes the perforations 2 in zone *d*, the air flows more directly upward and in the direction reverse to that of the 105 force of gravity. As the material passes over the perforations in zone *e* the enlivened mass is subject to the air pressure from the perforations 2 of said zone *e*, and in zone *f* the air is directed with the onflowing current of comminuted material, thus tending to lift it toward the top of the next riffle.

110 In the zone *g* the heavier material at the base of the riffle is brought to a standstill so far as the lateral onward movement is concerned and the lighter material is caused to ascend; this operation being hastened by the air from the perforations in zone *g* which air is directed up along the upper wall formed by the upper edge of the riffle. The 115 lighter material here rises responsive to the banking of its own accumulations, and to the pressure of air from the perforations in zone *g*. From this point the material flows on through succeeding zones *a*, *b*, *c*, etc., not 120 detailed in the drawing; the heavier material being carried along the table in both zones *b* and *g*. In the zone *b* a separation of the heavier gravities is effected by reason of the ridge 12 and a skimming process is therein 125 130

effected. As the heavier material increases in depth, and is moved longitudinally along the rear side of any riffle, the heavy values deposit on the rubber sheet, the pulp being 5 enlivened by vertically directed air flowing up from the perforations that are close to the upper or approach side of the riffle. On each cross section the onward flow is substantially such as shown; the overflow of the 10 lighter comminuted material occurring, however, at a lower level and this is repeated from riffle to riffle, there being a succession of zones *a*, *b*, *c*, *d*, *e*, *f* and *g* for each space between the approach sides of any two succeeding 15 riffles from end to end thereof; the depth of light material gradually decreasing and that of heavy material gradually increasing to the discharge end of the riffles. In this way a continuous skimming process 20 goes on at each riffle and each ridge, and very fine separations may be made between materials of different specific gravities. Such separations are made rapidly and the flow of comminuted material over the riffles where $\frac{1}{2}$ inch high may be a half inch in 25 depth, without loss of values, the flow being very rapid and continuous from the higher edge to the tailings discharge edge of the table, and the flow of the concentrates toward 30 the concentrates end of the table being facilitated by the ridges formed by the sheet when bent up by the air.

The lighter material commingled with the expanding air, moves transversely of the 35 table as freely as water but the delivery of the air thereto is effected so evenly that it does not raise dust. Although the air is given different directions by the perforations in the different zones, the air expands 40 and becomes diffused throughout the mass before it reaches the top surface of the pulp.

The air pressure bows the rubber sheet up between the riffles and thus opens the punctures more or less according to the angles 45 and the expansion and gives various directions to the air jets that issue therethrough; as will be understood from Figs. 3 and 4, with the result that the particles of comminuted material are shaken and tossed about and a 50 complete separation is effected without allowing any jet like escapes of air to occur; but the comparatively broad bars 3 extend beyond the onward face of the riffle so as to form a wind shield 20 thus affording a practically 55 dead air space in zone *b*, through which the pulp may fall from the top of the riffle. The approach sides of the bar and riffle are flush with each other.

For convenience of description the side *h* 60 of the riffle at which the pulp first arrives as it flows across the table top, is termed the approach side of the riffle; and that side *i* of the riffle over which the pulp falls in passing onward from the riffle is termed the 65 onward side of the riffle and so far as I am

aware I am the first to provide a concentrator table top constructed to form the successive zones above described, between the approach sides of two succeeding riffles.

By reference to Fig. 9 it will be understood that the longitudinal traces *j* of the table surface between and parallel to any two successive riffles are straight and practically level and that the tops of the riffles slope down to such surface in a manner customary to the riffles of former concentrator tables, and that the low ridge 12 extends to a practically uniform level between the riffles from end to end thereof, being lower than the riffle tops at 75 the head of the table, and higher than the riffles at the concentrates discharge end of the table so that the particles which are heavy enough to lodge before the ridge will pass on to the concentrates end of table and 80 will pass off without increasing the depth of the string of concentrates intercepted by the succeeding riffle.

In my application for Letters Patent of the United States, filed August 23, 1916, 90 Serial No. 116,555, I have shown a mineral separator comprising a table, a top therefor formed of a rubber sheet having slot like needle perforations therethrough that are normally closed and that are adapted to 95 be opened by air pressure; means whereby air pressure is applied therethrough from below to comminuted material to separate the gangue from the values, and means for delivering comminuted material to the table 100 top; and no claim is made herein to the subject matter just stated for the reason that the same is broadly claimed in said prior application. The present application is to specific construction and arrangements set 105 forth in the claims appended hereto.

I claim:—

1. A pneumatic concentrating table comprising a rubber sheet having therethrough numerous punctures normally closed by the 110 elasticity of the sheet; said sheet being exposed on its underside to pressure of air and having its upper side open to and in direct contact with air of lower pressure so that comminuted material passing over 115 the sheet in the air of the lower pressure will be directly subject to the said air of lower pressure and so action of the compressed and expanding air issuing through perforations formed by the opening of the 120 punctures caused by the passage of the compressed air therethrough will buoy up the lighter material; and riffles on the surface of the rubber sheet to catch the heavier material.

2. A concentrating table top comprising a sheet of elastic stretchable material having fine punctures normally closed therethrough, in combination with riffles on top of such sheet, said riffles and said top of the sheet 130

- 6 being in air of lower pressure, means to supply compressed air to the under-side of the sheet to stretch the same upward into said air of lower pressure and to open said 5 punctures to said upper air of lower pressure so that material in air of lower pressure may be subjected to a gravitational action according to the differences of pressure involved.
3. A dry ore concentrator table comprising 10 a frame, a stretchable rubber sheet fastened to the frame and provided with punctures that are normally closed; bars arranged at intervals apart below such sheet to support it and to intercept the passage 15 throughout of compressed air at intervals; riffle strips arranged on the sheet along above the bars and clamping the sheet on the bars in normal flat and unstretched condition; the riffle strips and top of the sheet 20 being subject to air of lower pressure; means to apply air pressure to the under side of the sheet to belly the same upwardly thus to open the punctures and supply a variable air pressure to the spaces between said 25 riffles, and means to apply differential motion to the tables.
4. In combination with a transversely inclined concentrating table frame having a differential reciprocating motion which carries 30 the material longitudinally forward toward the concentrates end of the table; a rubber sheet forming the top of the table, and riffles decreasing in depth toward the concentrates discharge end, fastened upon 35 said sheet; said sheet being punctured between the riffles with slits that are adapted to be expanded into perforations when the sheet is stretched upward; and means to apply air pressure to stretch the sheet and to 40 cause a flow of air through the perforations, and a flow of comminuted material over the riffles as the top is reciprocated.
5. A pneumatic concentrating table comprising 45 a rubber sheet having therethrough numerous punctures arranged in parallel rows and normally closed by the elasticity of the sheet said sheet being exposed on its underside to pressure of air and having its upper side open to air of lower pressure so 50 that comminuted material passing over the sheet in the air of the lower pressure will be directly subject to the action of the compressed and expanding air issuing through perforations formed by the opening of the 55 punctures caused by the passage of the air therethrough; riffles extending in parallelism with the rows; there being a plurality of rows of punctures between the riffles; the rubber sheet being adapted to bow upward 60 in ridges respectively between the riffles whereby varying passages for the compressed air are opened up below the riffles; and means to give differential motion to the table longitudinally of the riffles.
6. A concentrating table top comprising 65 a sheet of elastic stretchable material having fine punctures normally closed therethrough, in combination with riffles on top of such sheet, means to supply compressed air to the under-side of the sheet to stretch the 70 same upward into air of lower pressure and to open said punctures to said upper air of lower pressure according to the differences of pressure involved and according to the various angles and expansions of the sheet; 75 said table top being aslant transversely of the riffles and means to apply differential motion to said table top.
7. A dry ore concentrator table comprising 80 a frame, a stretchable rubber sheet fastened to the frame and provided with punctures that are normally closed; bars arranged at intervals apart below such sheet to support it and to intercept the air at intervals; riffle strips arranged on the sheet 85 along above the bars and clamping the sheet on the bars in normal flat and unstretched condition; said bars forming wind brakes at the onward side of the table; means to apply air pressure to the under side of the 90 sheet to belly the same upwardly thus to open the punctures and supply a variable air pressure to the spaces between said riffles according to the various angles and expansions of the sheet, and means to apply 95 differential motion to the tables.
8. A concentrator table having a riffled top and provided between the riffles with punctures through which air under pressure may be forced; said top being provided, 100 while in action with longitudinal ridges between the riffles; said ridges being lower than the riffles and provided with said punctures.
9. A concentrator table having a riffled 105 top and provided between the riffles with a surface having punctures through which air under pressure may be forced; said top being provided, while in action with longitudinal ridges between the riffles; said ridges being lower than the riffles and provided with said 110 punctures; and wind brakes at the onward sides of said riffles to allow the comminuted material to fall to said surface as it passes over the riffle.
- 115 10. A dry concentrator table for gravitational separation of comminuted material, comprising an air pressure chamber having a permeable top formed with bars, a thin rubber sheet, and riffles, which riffles and upper face of the thin rubber sheet are subjected to a predetermined air pressure; said sheet having slits therethrough and applied to the upper side of said bars; and the riffles being on the sheet directly over the bars and being formed of strips reduced in depth from the head of the table toward the concentrates end of the table and being fixed to the top of the sheet; said rubber sheet being punctured with slits that are normally 120 125 130

- closed to resist initial pressure of air within the chamber and adapted to open into air of predetermined pressure under additional pressure within the chamber when such additional pressure becomes great enough to bend and stretch the rubber upward at intervals underneath the load of comminuted material on the table.
11. A dry concentrator table adapted for gravitational separation of comminuted material, comprising an air pressure chamber having a permeable laterally inclined top formed with bars, a thin rubber sheet and riffles; the thin rubber sheet having slits therethrough and being applied to the upper side of said bars; and the riffles being formed of strips reduced in depth from the head of the table toward the concentrates end of the table; the riffles and top surface of the sheet being subject to a predetermined air pressure; the longitudinal traces of said table being level and the tops of the riffles slanting down toward the table top from head to concentrates charge; said rubber sheet being punctured with slits that are normally closed to resist initial pressure of air within the chamber and adapted to open under additional pressure when such pressure becomes great enough to bend and stretch the rubber upward underneath the load of comminuted material on the table; means to supply comminuted material to the head of the table, and means to supply air pressure to the underside of the rubber sheet.
12. A pneumatic concentrator table top comprising supporting bars and riffles superposed thereon and a thin stretchable rubber sheet clamped between said bars and riffles; said sheet being provided with punctures that are adapted to form slits to allow compressed air to pass therethrough when the sheet is stretched by air pressure from below; said slits being arranged in rows that extend parallel to the sides of the riffles and also being arranged with their longer axes oblique to the axis of the row and to the side of the riffles.
13. A pneumatic concentrator table top comprising supporting bars and riffles superposed thereon and a thin stretchable rubber sheet clamped between said bars and riffles; said sheet being provided with punctures that are adapted to form slits to allow compressed air to pass therethrough when the sheet is stretched by air pressure from below; said slits being arranged in rows that extend parallel to the sides of the riffles and also being arranged with their longer axes oblique to the axis of the row and to the side of the riffles; the spaces between the rows being of greater width than the spaces between the slits of a row.
14. A pneumatic concentrator table top for gravitational separation of comminuted material, comprising a punctured stretchable rubber sheet; supports therefor and riffles on top of the sheet above the supports, the sheet and riffles above the sheets being subjected to a predetermined air pressure; there being punctures in the sheet between the riffles adapted to allow air under pressure to flow up through rubber to buffet the comminuted material according to the stretching of the rubber by compressed air from below.
15. A pneumatic concentrator table top constructed of a punctured stretchable sheet and riffles arranged to form zones where the pulp is subjected to varied operations of forces in succession in the order named; that is to say, frictional zone for action of a riffle, practically unobstructed gravitational descent from the riffle top; action of expanding air directed toward the onward side of the falling pulp; a zone for retardation of onward flow of pulp, said zone being formed by a gentle ascent of the sheet; means to cause expansion of upwardly directed expanding compressed air; means to cause expansion of compressed air directed with the onward flow of the pulp; means to cause a banking of the pulp against the approach side of a riffle; and means to cause the expansion of compressed air directed upwardly at the approach side of the riffle.
16. In a dry concentrator of the class specified; a permeable and stretchable sheet rubber table top surface and riffles along the surface; there being a low ridge between each two successive riffles subject to variations of pitch as the relative air pressures vary.
17. In a dry concentrator of the class specified; a permeable table top surface and riffles along the surface; there being a low ridge between each two successive riffles, the permeable surface having perforations that in action direct air toward the pulp approaching the ridge on one side and with the flow of pulp on the onward side of the ridge.
- In testimony whereof I have hereunto set my hand at Los Angeles, California, this 14th day of June, 1918.
- CHARLES W. ECCLESTON.
- Witness:
- JAMES R. TOWNSEND.
